ABSTRACT OF THE DISCLOSURE

The apparatus is a digital voltmeter employing an integrator for storage of an unknown signal and means to incrementally discharge the integrator to a predetermined level. The unknown signal is applied to the integrator by first applying the unknown signal to a reactive impedance storage element and thereafter transferring the stored signal to the integrator.

This invention relates to digital voltmeters, that is to any voltmeters which incorporate a counter in which a measure of the applied voltage is obtained as an integral number. In practice the counter may be binary, binary coded decimal or decimal and may give a visual display, command a printer or act as a direct source of coded information to a computer. It will be understood that, although the term voltmeter is used as is customary because instruments of the type in question are most commonly used to measure potential, the instruments may of course also be applied to the measurements of current, charge or other related quantities.

One known form of voltmeter generates a ramp voltage which is compared with the applied voltage. Clock pulses are gated into the counter from the time of commencement of the ramp until the ramp voltage equals the applied voltage. It is difficult and expensive to design a ramp generator of high linearity and this method is ordinarily restricted to voltmeters of moderate precision, 1% to 0.1%.

Another known form of voltmeter compares the applied voltage with the output of a set of switches with weighted outputs forming a binary or binary coded decimal series. Controlling logic compares the applied voltage with the weighted outputs in descending order of magnitude, each freshly switched-in weighted output being left in if the total is less than the applied voltage but switched out again if the total exceeds the applied voltage. Assuming a binary series of weights the total number of comparisons is $\log_2 S$ where S is the "range number" or ratio of the "full-scale" reading to the lowest determinable input. Such comparisons can be carried out in the time of $\log_2 S$ clock pulses whereas the previous method requires S clock pulses for a "full-scale" reading. The gain of speed is important and the voltmeter may be made very accurate but $\log_2 S$ precision resistors are necessary and $\log_2 S$ switches which must be relays or precision diode clamps. This method is therefore expensive.

In order to obtain precision without expense it has been proposed to apply the voltage to be measured to an integrating amplifier for a measured number of clock pulses and thereafter to count the number of times that a standard quantum of charge must be applied to the amplifier to bring its output back to zero. Alternatively the said voltage is applied continuously and a short-term stable oscillator determines clock intervals in each of which a quantum of charge is or is not applied, depending on whether the amplifier output exceeds or is within a given

threshold level. The magnitude of the applied voltage is given by the ratio of the number of quanta of charge applied to the number of clock pulses in any suitable interval. In either event two counters are implied: one for counting a standard number of clock pulses and another for counting the number of quanta of charge applied. Very few precision components are required however and accuracy can be obtained at moderate cost.

The object of the present invention is to reduce the cost of a high accuracy digital voltmeter even further by eliminating the need for more than one counter. In addition, no oscillator is necessary in carrying out this invention although such may be used for a special purpose as subsequently explained.

According to the invention a digital voltmeter comprises a reactive impedance, means for switching the impedance initially to a signal to be measured to establish a voltage across or current in the impedance, means for thereafter connecting the impedance to a feedback amplifier whose output is applied to a level discriminator under the control of which a standard increment of charge or current is repeatedly applied to the amplifier in opposition to that applied by the impedance until the amplifier output level returns to a datum value and a counter arranged to count the number of the said increments.

The reactive impedance is preferably a capacitor across which the voltage to be measured is initially established and from which increments of charge are then removed until the voltage returns to a datum, say 0 volts, but the preceding, broader statement of invention takes into account the duality between a capacitor and voltage (or current) on the one hand and an inductor and current (or voltage) on the other hand.

For reasons which will hereinafter be explained the amplifier is preferably of substantial negative gain and shunted by a capacitor. A resistor or resistive circuit is preferably placed in series with the first-mentioned capacitor and this resistor or circuit may be so arranged that the current from the first-mentioned capacitor is approximately constant over a range of voltages across the capacitor.

The invention will now be described in more detail by way of example with reference to the accompanying drawings, in which:

FIG. 1 is a circuit diagram of one embodiment of the invention;

FIG. 1b illustrates a modification of FIG. 1;

FIG. 2 is an explanatory diagram; and

FIGS. 3 and 4 are circuit diagrams illustrating two further modifications to the circuit of FIG. 1.

In FIG. 1 the voltage to be measured is applied to terminals T. A first capacitor C_1 in series with a first resistor R_1 is connected by a two-pole switch $S1_a$, $S1_b$ first to the input voltage to be measured and then between system ground and the input of an "operational" amplifier A shunted by a second capacitor C_2 . The output of the amplifier is applied to a level discriminator D.

The level discriminator may take any suitable conventional form, as described for example in "Waveforms" pp. 358 (vol. 19 of the M.I.T. Radiation Laboratory Series). Typically it will consist of a difference amplifier DA with one input grounded and the other connected to the output of the amplifier A and a relay DR forming the difference amplifier load. The relay has three spring sets. One set S4 is used in known manner to cause the relay to operate repeatedly when the output level of A departs from the datum value. The second set is the contacts S2 whose purpose is described below and the third set S5 operates the counter B.

When the output of the amplifier A exceeds a certain level, for example goes negative with respect to system ground, the level discriminator operates the switch S_2

and the counter B, causing the counter to add once and this addition will occur repeatedly so long as the said level is exceeded. Operation of S1 causes a capacitor C₃, previously charged to reference $-V_R$ to discharge into the input of the amplifier A. V_R may be a standard cell or for example, the drop across a Zener diode. It is important that the peak charging and discharging currents of C₃ be limited by a resistor R₂, and then that the period of dwell of S₂ in each position be sufficient substantially to charge and to discharge C₃.

If the initial state of A is that its input is zero and its output close to the threshold of D, and if the input voltage has the correct sense, then D will continue to cause S₂ to operate and B to count, until the voltage at A has returned to zero. Since A is an "operational" amplifier, i.e. the product of its gain and its input resistance is large, this occurs when there is no net charge at its input. The condition for this is that

$$V_1 C_1 + N V_R C_3 = 0$$

where V_1 is the input voltage, and N is the count in B. Thus

$$V_1 = N (V_R C_3 / C_1)$$

and if V_R , C₁ and C₃ are all established with precision, N is a measure of V_1 .

The resistor R₁ is not essential but limits the current into the amplifier. In the discussion so far, the role of C₂ has not emerged and, indeed, the device would work as described without this capacitor. We shall now examine the output waveform of A, and show reasons for including this component.

The input of A is a virtual earth, and into it are fed three currents whose sum is substantially zero, viz:

$$V_1 / R_1 \exp(-t/C_1 \cdot R_1) - V_R C_3 n + C_2 dV_2 / dt = 0$$

where t is the time elapsed since connecting C₁ to A, n is the number of actuations per second of S₂, and V_2 is the amplifier output voltage, here assumed to be zero when $t=0$. Integrating and solving for V_2 we have

$$V_2 = V_R C_3 / C_2 \int_0^t n dt - V_1 C_1 / C_2 \exp(-t/C_1 \cdot R_1)$$

The first and second of these terms are illustrated in FIG. 2 marked I_a and II respectively; their sum is depicted by the dashed-line voltage waveform in this figure marked V₂. In FIG. 2, it has been assumed that the sum is initially negative. It will be seen that V₂ first moves to a minimum and then returns to zero; during all of this time, n is constant at the maximum rate at which the relay DR has been designed to operate. At the point P, while V₂ returns to 0, a new regime sets in; V₂ remains nearly at zero and n decreases in such a way that the prolongation of curve I_a, namely I_b, is nearly the mirror image of II. Finally, at time t_0 , when S₂ has ceased to act, the process is completed and the switch S1 may be returned to the position shown in FIG. 1.

The circuit described is a compromise among various desirable features, one being to make t_0 as short as possible for a given maximum rate of n and a given range number S. This makes a prolonged regime I_a desirable. Otherwise it would be necessary to increase R₁ and hence t_0 . It is also desirable to make the peak excursion of V₂ as small as possible and this shows why the capacitor C₂ is desirable.

In the alternative arrangement shown in FIG. 1b, the relay DR is replaced by an astable (or free-running) multivibrator MV which is shut off so long as the output level of the amplifier A does not exceed the datum value, but which runs whenever the datum level is exceeded. The multivibrator can be coupled capacitively to the counter B and S₂ is replaced by a conventional arrangement of transistor switches S_{2a} and S_{2b} transformer coupled to the multivibrator.

In a modification of the invention, we substitute for

R₁ a device passing a substantially constant current in response to a suitable wide range of impressed volts. This current is made just less than the maximum obtainable from S₂. One form of suitable constant-current resistance is that manufactured by the Circuitdyne Corporation, California under the trade name of Currectors. Another, and preferred modification is shown in FIG. 3.

The level discriminator D now need consist only of a difference amplifier whose output goes to two gates. The first, a sharp on-off gate G₁ is fed with a train of square waves from an oscillator O and passes these, all or none, to the switch S₂, e.g. the transistorised switches S_{2a} and S_{2b}. Each square wave reaching the switch causes C₃ to discharge into A once. These square waves are also applied to the counter B. The second gate, a proportional gate G₂, is fed with triangular waves (formed by integration of the square waves) and passes the peaks of these, to a greater or less extent varying reversely with the amount of negative voltage out of D, to a chopper H in series with a resistor R₁ of much decreased value. H is turned on with a variable mark/space ratio and so automatically adjusts the rate of discharge of C₁ so as to maintain V₂ slightly negative. The circuit constants are chosen so that when V₂ is permissibly negative the current from C₁ never exceeds the current from S₂. G₂ may alternatively be referred to as a clipper, with clipping level set by D.

In order to achieve the conditions outlined above it is merely necessary to adjust the relative sensitivities of the gates G₁ and G₂ appropriately. For example, the amplifier A may have a saturation output of 30 v. and the level discriminator D may have a voltage gain of 30 and saturate at 10 v. output, corresponding to 330 mv. out of A. The gate G₂ may be so biased that only the tops of the triangular waves are passed when the output of D is 10 v. but increasing portions of the waves are passed as the output of D falls below this saturation level. G₁ is however arranged to open at 300 mv., corresponding to 10 mv. out of A.

As the input of A is restored at the end of each cycle of S₁ nearly to zero and its output nearly to the level at which D operates, very little demand is made on its drift stability. It may, however, be A.C. coupled with a time-constant of at least the order of the time-cycle of S₁.

Means for extending the range can consist of switching means for a set of capacitors C₁ with or without simultaneous switching of R₁, or they can consist of the circuit of FIG. 4. Here the range is extended in the ratio 1:1+C₁/C₁' by the switch S₃. This arrangement is particularly suitable for use with a chopper in place of R₁.

When S₁ is a 2-pole switch, it can also be made reversing to read a voltage of either polarity. A level discriminator responsive to positive voltage can then be added to reverse the switch S₁ and/or affect other suitable parts of the apparatus including indicating means, in order to provide automatic response to an input of either polarity.
